UNITED STATES PATENT OFFICE.

CHARLES A. HUNT, OF NEWBURGH, NEW YORK.

SASH-FASTENER.

1,111,585.

Specification of Letters Patent. Patented Sept. 22, 1911.

Application filed January 10, 1913. Serial No. 741,256.

To all whom it may concern:

Be it known that I, CHARLES A. HUNT, a citizen of the United States, residing at Newburgh, in the county of Orange and State of New York, have invented new and useful Improvements in Sash-Fasteners, of which the following is a specification.

This invention relates to sash fasteners; and it has for its object the provision of a device of this character which when operatively arranged upon the sashes will positively prevent the same from being opened.

With these and other objects in view, the invention consists of certain novel features of construction, combination and arrangement of parts, as will be hereinafter described and claimed.

In the accompanying drawings: Figure 1 is a perspective view of companion upper and lower sashes, showing the fastener applied thereto; Fig. 2 is a vertical section on line 2—2 of Fig. 1, showing the wedge in sash locking position; Fig. 3 is a view similar to Fig. 2, showing the wedge adjusted to permit the sashes to be slid to predetermined positions; Fig. 4 is a view similar to Fig. 2, showing the initial contact of the lower sash with the wedge so as to adjust the latter to a required locked position; Fig. 5 is a horizontal section on line 6—6 of Fig. 1; and Fig. 6 is a perspective view of the wedge.

Referring more particularly to the drawing the upper sash U is provided along one of its side bars with a metallic rack 1, which is vertically-disposed and provided along its longitudinal edges with guideways 3 for the reception of the side flanges 4 of a vertically sliding wedge 5. This wedge has its flanges extended preferably at right angles from the side walls 6, the latter terminating at their upper ends below the top 7 of the wedge, while the side walls 6 are extended in an outward direction from the upper edges of the flanges 4, so as to provide effective locking points 7'. The flanges 4, through their frictional contact with the walls of the vertical guideways of the rack bar, are adapted to securely hold the wedge in any adjusted position between the ends of the rack bar so that it may be maintained at

a point as may depend upon the predetermined adjustment that may be desired of the respective sashes.

The lower sash L is provided at its meeting rail R with a recess 9, the wall 10 of which lying parallel with the inclined surface 10' of the wedge. When the upper sash is moved in a downward direction, or the lower sash moved in an upward direction, the rack bar of the upper sash is disposed across the recess of the said lower sash so that the wall 10 of the recess will be brought to bear against the inclined surface of the wedge, whereupon the wedge will be moved laterally so as to cause the effective locking points of the side walls 6 to be presented into one of the passages 11 of the rack bar where they will be engaged beneath the adjacent connecting bar or tooth 12. From this construction it is seen that the wedge is both longitudinally and laterally shiftable in the guideways of the rack bar. It is evident that the wedge may be placed at any point in the length of the rack bar as may depend upon the adjustment that is desired of the respective sashes. Moving the sashes to closed position causes a relative separation of the inclined surface of the wedge from the inclined wall 10 of the recess 9 so that no manual operation to effect a release of the wedge is necessary. It is also apparent that the lock is rendered operative irrespective of the sash adjusted. In other words, it is said that the wedge will be brought into proper locking position on movement of the lower sash in an upward direction or a movement of the upper sash in a downward direction.

Various changes in the form, proportion and the minor details of construction may be resorted to without departing from the principle or sacrificing any of the advantages of this invention, as claimed.

Having thus described my invention, what I claim is:—

In a sash fastening, upper and lower sliding sashes, a rack bar carried by the upper sash and provided with longitudinal guideways, a wedge slidably mounted upon the rack bar and provided with flanges extending into the guideways, the said wedge be-

ing exposed beyond the side of the rack and positioned to engage the lower sash, and means on the wedge adapted to be advanced into effective locking engagement with the teeth of the rack bar on engagement of the wedge with the lower sash, said means consisting of a pair of locking teeth extended in an upward and outward direction from the flanges at the upper end of the wedge,

and disposed at right angles to the said flanges.

In testimony whereof I affix my signature in presence of two witnesses.

CHARLES A. HUNT.
